ABSTRACT: A target practice device is described for use in fixed aiming target practice, comprising a target disk movable in front of a target sheet and formed with a central opening for marking, a pair of rails extending perpendicular to each other, the target disk being movable on one rail, in one direction while the latter rail is movable with the target disk on the second rail in a perpendicular direction, and a remotely-controlled electric drive for moving each of the foregoing along its respective rails, each drive including a screw shaft rotated in either direction by an electric motor and a nut connected to the assembly moved by its drive. Also described are means, e.g. the trigger of the rifle aiming device, for actuating a marking device, and means for automatically restoring the target disk to its initial position.

TARGET PRACTICE DEVICE

BACKGROUND OF THE INVENTION

1. Field of the Invention

The present invention relates to target practice devices, particularly for use in the "triangulation" method of fixed aiming target practice.

2. Description of the Prior Art

During the training of recruits or beginners, they usually engage in aiming practice only so as to save ammunition. In the "triangulation" method of fixed aiming target practice, the fixed aiming device, e.g. a rifle supported on a sand bag or other fixed support, is aimed by the trainee at a target disk held by an assistant by means of a long handle in front of a white target sheet. This target disk is generally in the form of a round metal sheet of about 10 cm. diameter having at its center a black painted bulls eye and a small hole through which a marking pencil can be passed. The trainee indicates, by signs or calls, to the assistant for the latter to move the target disk in the proper direction until the trainee feels the bulls eye in in the line of his sights. The assistant then marks the point on the target sheet by means of a pencil or other marking device passed through the hole in the bulls eye.

This is repeated three times and theoretically the three points should coincide since the position of the rifle has not been changed. However only in very rare cases is the coincidence of the three points actually reached. Where the points do not coincide, they are connected by lines forming a triangle, and the smaller the triangle, the better was the aiming ability of the trainee. In this manner, the trainee may be classified according to his aiming ability, and also his progress may be followed without expending expensive ammunition.

One of the drawbacks of this method is the need for an assistant for each trainee, apart from the instructor. In addition, even with trained personnel it may happen that the target disk is slightly shifted while passing the pencil through the hole in the center thereof, and the result obtained would thus not indicate the true condition of the trainee's aiming ability.

Another arrangement is known wherein a target sheet on which a target has been indicated is shifted by the trainee himself with the aid of pulling cords to one or the other direction until he believes the target to be in line with the sights. The trainee may also operate a marking element by means of another pull rope to record the results of the aiming on a separate strip of paper. In this arrangement, however, there is the disadvantage, among others, that the operation of the pull ropes makes it difficult for the trainee to aim properly.

SUMMARY OF THE PRESENT INVENTION

The present invention provides a target practice device in which the target disk may be remotely controlled by the trainee, or user, in a very simple manner.

According to the present invention, is provided a target practice device for use in fixed aiming target practice, comprising a movable target disk and a target sheet disposed behind the movable target disk, the target disk being formed with a central opening for marking on the target sheet, as in the known arrangements. Here, however, there are provided a pair of rails extending perpendicular to each other, the target disk being movable on one of the rails in one direction and the latter rail being movable with the target disk on the other rail in a perpendicular direction. A pair of screw shafts are provided each extending parallel to one of the rails there being an electric motor for driving each of the screw shafts. Further, a nut is fixedly carried by the target disk and is movable by one of the screw shafts for moving the target disk along the one rail, and a second nut is fixedly carried by the one rail and is movable by the other screw shaft for moving the one rail and the target disk along the other rail. A switch is further provided for controlling each of the electric motors.

According to another feature of the invention, there is also provided an arrangement, e.g. the rifle trigger, operable by the trainee for actuating the marking device. A further feature of

the invention provides means operable after the marking has been effected to automatically return the target disk to its initial position at the edge of the target sheet.

BRIEF DESCRIPTION OF THE DRAWINGS

The invention is herein described, somewhat diagrammatically and for purposes of example only, with reference to the accompanying drawings, wherein:

FIG. 1 illustrates a target practice device constructed in accordance with the invention;

FIG. 2 illustrates the aiming device, namely a fixed rifle, for use with the target practice device of FIG. 1; and

FIG. 3 is a wiring diagram of the target practice device of FIGS. 1 and 2.

DESCRIPTION OF THE PREFERRED EMBODIMENT

With reference to FIG. 1, on a supporting structure 1 there is mounted a white target sheet 2. At the right-hand top corner of the sheet is positioned the target disk 3 fixed to a carrying bar 4. The position shown may be considered as its initial or zero position. A mechanism generally designated 5 is carried by the supporting structure 1 and serves to move the target disk 3 to any desired position with respect to sheet 2.

Mechanism 5 comprises two guide rails 6, 7 which extend perpendicular to one another, and a pair of screw shafts 8, 9 each extending parallel to one of the guide rails 6, 7. To each of the screw shafts is coupled a reversible electric motor 10, 11, controllable by the user, i.e., the trainee or the aiming person. A nut 12, 13 is threaded on each of screw shafts 8, 9. Nut 12 is fixed to the end of bar 14 which carries disk 3. Bar 14 also carries a sleeve 6a through which rail 6 passes. Thus, bar 14 and disk 3 are moved as a unit up and down on rail 6.

Rail 6 is connected by a connecting piece 8a to screw shaft 8, and the latter assembly is movable on rail 7 by means of three sleeves 7a through which rail 7 passes, these sleeves being affixed to a plate 7b on which motor 10 is supported. The drive shaft of motor 10 is perpendicular to screw shaft 8 and drives the latter by a bevel gear 10a. The middle one of the sleeves 7a is fixedly connected by a connecting piece 7c to nut 13 whereby the assembly carried on rail 6 may be moved along rail 7 in a direction perpendicular to rail 6.

During target practice, the trainee looks through the customary sights 15, 16 provided on the rifle 17 (FIG. 2). The rifle is fixedly held in a holding arrangement 18 of customary design and is built in such a way that after release of the holding clamps (not shown) the rifle can be swung upwardly as well as laterally. In this way, the rifle can be aimed by the instructor at a chosen point on sheet 2 and can be fixed in position. It is of course possible to use other aiming devices.

Electric motors 10 and 11 may be controlled by the trainee e.g. by a four-way switch 19, FIG. 3, to be described below), so as to move the target disk up, down, left or right. Thereby it becomes possible to locate the target disk 3 onto any chosen point of the target sheet 2. If the target disk is in a position which gives the trainee reasonable certainty that a round from rifle 17 would hit the center of the disk 3, that is to say that this disk is in coincidence with the line of vision, the trainee can mark this point on the target sheet. To this end he operates a switch, preferably by pressing the trigger of the rifle as will be described below, which actuates a marking device 20 provided on the target disk 3 to mark a point on sheet 2 through opening 21 in the center of the disk. This may be effected by actuating an electromagnet or motor to move a pencil or stylus against the sheet. Once the marking has been completed, target disk 3 returns automatically to the initial or zero position illustrated in FIG. 1.

Two signal lamps 22 (FIG. 1) may be provided, one of which may be red and the other white. These lamps could be wired so that the red lamp is energized during aiming, and the white lamp is energized after termination of the marking. This arrangement facilitates the tasks of a supervising person and gives a better picture of the stages and conditions of the practice.

FIG. 3 illustrates a wiring diagram in which the target device 4 is automatically returned with the return of the rifle trigger, or other button used for operating the marking arrangement. The return of the target device 4 is effected by motors 10 and 11 which are energized upon the return of the rifle trigger, these motors being deenergized by two contacts A₁ and A₂ which are opened when the target disk 3 returns to its initial position, i.e. its uppermost position at the right-hand side of sheet 2 as illustrated in FIG. 1.

More particularly, the trainee directs the target disk 3 to the desired position by operating four-way switch 19 to supply current to the fields F of motors 10 and 11 in the forward or reverse direction. As soon as the target disk leaves its initial position, contacts A₁ and A₂ close. When the disk arrives to the position which the trainee feels is in alignment with the rifle sights, he presses the rifle trigger, operating switch Z, which thereby energizes relays B and C, and also energizes the actuator M (e.g. a solenoid or motor) of the marking device 20, which applies a mark through the central opening of the target disk 3 onto the sheet 2. When the trainee releases the rifle trigger, the switch Z returns to its initial position as illustrated in FIG. 3.

Energization of relays B and C causes their holding contacts B₁, C₁ to be actuated, thereby retaining the energization of the relays even when the rifle trigger and the switch Z return to their initial position.

Energization of relays B and C also causes their contacts B₁ and C₁ to close, these contacts being in the circuits of relays E and D. However, the latter relays are not energized until the rifle trigger and switch Z return to their initial positions. As soon as this occurs, relays E and D are energized through switch Z, closing their contacts E₁, E₂, D₁, D₂ and opening their contacts E₃, E₄, D₃, and D₄.

Closing contacts E₁, E₂, D₁ and D₂ causes the motors 10 and 11 to operate to return the target disk 3 to its initial position. During this return of the target disk, the four-way switch 19 is disconnected from the motor control circuits by the opening of contacts E₃, E₄, D₃ and D₄. When the target disk 3 is returned to its initial position, contacts A₁ and A₂ are automatically opened, thereby deenergizing relays B and C, causing the latter to open their contacts B₁, C₁, thereby also deenergizing relays E and D. The deenergization of the latter relays causes their contacts E₁, E₂, D₁, D₂ to open, thereby terminating the operation of the motors 10 and 11, and also causes their contacts E₃, E₄, D₃, D₄ to close, connecting the four-way switch 19 into the motor control circuits for operation again.

by the trainee.

It is preferable to use a low voltage power supply, e.g. a battery power supply or an AC power supply fed through a low-voltage transformer.

5 The invention may be practiced in various manners. For example, the motors may be operated by a portable wireless transmitter. It will be seen that extra personnel for working the target disk is not required and that one instructor is sufficient to supervise several targets. Instead of a single target sheet, 10 there may be used a block of sheets, one being removed by each person engaging in the target practice.

Many modifications, variations, and other applications of the illustrated embodiment may be made.

We claim:

15 1. A target practice device for use in fixed aiming target practice, comprising: a target disk movable in the horizontal and vertical directions; a target sheet disposed behind said movable target disk, said target disk being formed with a central opening for marking on the target sheet; an electrical

20 motor drive for moving the target disk in the horizontal and vertical directions from an initial position; an electric switch for actuating said electric motor drive to move said target disk in the horizontal and vertical directions from its initial position; a marking device carried by said target disk; means 25 operable by the user for actuating said marking device to apply a mark on said target sheet; and means for automatically returning the target disk to its initial position after actuation of the marking device.

2. A device as defined in claim 1, wherein said target disk is 30 movably supported by means of a pair of rails extending perpendicular to each other, said target disk being movable on one of said rails in one direction, said one rail being movable with said target disk on the other rail in the other of said directions.

35 3. A device as defined in claim 2, wherein said electric motor drive comprises a pair of screw shafts each extending parallel to one of said rails, an electric motor for driving each of said screw shafts, a nut fixedly carried by said target disk and movable by one of said screw shafts for moving the target disk along said one rail, and a second nut fixedly carried by said one rail and movable by the other of said screw shafts for moving said one rail and the target disk along said other rail.

40 4. A device as defined in claim 1, further including a rifle 45 serving for the fixed aiming, said means for actuating the marking device being the trigger of said rifle.
